his ATTORNEY

UNITED STATES PATENT OFFICE.

WILLIAM BUORNAT, OF UTICA, NEW YORK.

FIGURE TOY.

1,414,501.

Specification of Letters Patent. Patented May 2, 1922.

Application filed June 18, 1921. Serial No. 478,508.

To all whom it may concern:

Be it known that I, WILLIAM BUORNAT, a citizen of the United States, residing at Utica, in the county of Oneida and State 5 of New York, have invented certain new and useful Improvements in a Figure Toy, of which the following is a specification.

The main object of this invention is the provision of a toy inexpensive in cost of 10 manufacture and attractive as a plaything for children.

The above and other objects will become apparent in the description below, in which like-named characters of reference refer to 15 like-named parts in the drawings.

Referring briefly to the drawings, Fig. 1 is a front elevational view of my toy.

Fig. 2 is a side elevational view of the same.

20 Referring now in detail to the drawings, the numeral 1 represents the base of the device, having rigidly mounted on either side thereof supports 2 and 3, respectively, in the shape of the legs of men. The bodies 25 4 and 5 of the figures are pivotally mounted on said legs 2 and 3, respectively. The body 4 is provided with an eyelet 6 in which a rod 7 has pivotal engagement. Said rod extends into a compartment provided in the 30 base and is pivotally attached to one arm 10 of a three-armed crank 8 pivotally mounted in said compartment. Buttons 11 and 12 are

slidably mounted in the outer wall of said compartment and are pivotally attached to the other two arms of said crank. The arms 35 14, and 15, respectively, of the figures 4 and 5, are pivotally secured to their respective bodies and the extremities thereof are pivotally attached to the ends of a member in the form of a saw. A log is represented as 40 shown under said saw.

In operation, it is apparent that, upon pushing in alternately one button and then the other in the side of the base 1, the figures will be made to rock so that the whole 45 will represent two men sawing a log.

I claim:

A device of the class described comprising a base, a compartment near the edge of said base, a figure of a person on said base 50 having the body thereof pivotally attached to the leg, said leg being rigid with said base, an eyelet in said body, a rod pivotally attached to said eyelet, said rod extending into said compartment, a three-armed crank pivotally mounted in said compartment, buttons 55 slidably mounted in the outer wall of said compartment and having pivotal engagement with two of the arms of said crank, said rod being pivotally connected 60 with the third of said arms.

In witness whereof I affix my signature.

WILLIAM BUORNAT.
